(57) **CLAIM**

The ornamental design for a commemorative vessel, as shown and described.

DESCRIPTION

FIG. 1 is a front perspective view of a commemorative vessel showing the new design;

FIG. 2 is a front elevational view thereof;

FIG. 3 is a rear elevational view thereof;

FIG. 4 is a side elevational view thereof;

FIG. 5 is an opposite side elevational view thereof;

FIG. 6 is a top view thereof; and,

FIG. 7 is a bottom view thereof.

The broken lines shown in the drawing are for the purpose of illustrating portions of the commemorative vessel and form no part of the claimed design.
